UNITED STATES PATENT OFFICE.

CHARLES E. CARPENTER, OF MINNEAPOLIS, MINNESOTA, ASSIGNOR TO THE CARPENTER-NEVENS ELECTRO-HEATING COMPANY, OF SAME PLACE.

ELECTRIC SOLDERING-IRON.

SPECIFICATION forming part of Letters Patent No. 433,671, dated August 5, 1890.

Application filed May 10, 1890. Serial No. 351,268. (No model.)

To all whom it may concern:

Be it known that I, CHARLES E. CARPENTER, a citizen of the United States, residing in the city of Minneapolis, in the county of Hennepin and State of Minnesota, have invented certain new and useful Improvements in Electric Soldering-Irons, of which the following is a specification.

This invention relates to improvements in electric soldering-irons, in which heretofore the resistance or electrical conductor has been wound or disposed about a cylinder or body of copper provided with a tapering head, to which the heat generated in the resistance is conducted through the medium of the body, the resistance or body being covered with some heat-insulating material, leaving only a tapering head or point of the iron exposed. It is obvious and well understood that with such a construction there is considerable waste of energy or current, because of the great radiating or heating surface of the body, which must first be heated to a high degree before the head or point of the iron, which can alone be utilized in practice, is heated to a sufficient degree. Besides which, practice has demonstrated that the space is too small to provide sufficient heat-insulation between the outside covering or casing and the body or cylinder portion of the iron, and hence the casing will be heated to a temperature sufficiently high to be not only extremely objectionable, but wasteful of much of the energy supplied to the iron.

The prime object of my invention is to heat and confine the heat only to that portion of the iron which is employed in practice—that is, the head or point thereof—whereby the compactness, simplicity, and effectiveness of the iron is promoted to the maximum degree, while the iron is rendered much lighter and therefore easier of manipulation and more economical in use.

Another object is to dispense with the cylindrical body portion of the iron and the accompanying heat-insulation and the casing therefor, and at the same time have the handle of the iron so connected with the heated portion thereof as to avoid the objectionable heating of the same.

A further object is to have the iron of such

construction that any desired degree of pressure may be employed in binding the elements together, whereby the effect of the heat evolved from the resistance or electrical conductor will be greatly intensified and the elements at the same time held in fixed relation to each other against shifting induced by jarring or otherwise.

These objects are attained by the devices illustrated in the accompanying drawings, in which—

Figure 1 represents a central longitudinal section through a soldering-iron embodying my invention; Fig. 2, a transverse vertical section thereof on the line 2 2 of Fig. 1; Fig. 3, a detail longitudinal section through the iron, showing a modified construction thereof; and Fig. 4, a detail side elevation of a modified form of core.

Similar letters of reference indicate the same parts in the several figures of the drawings.

This iron, so far as relates to the general disposition of its elements—that is to say, the resistance or electrical conductor and the electrical insulations thereof—is somewhat similar to that shown in my application for Letters Patent, Serial No. 344,354, filed March 18, 1890, upon which this invention is more especially designed to be an improvement, but is wholly different in its general features of construction.

Referring now by letter to the accompanying drawings, A indicates a core having the contour of a frustum of a cone, the conical surface of which is covered with a layer of electrical insulating material B, of uniform thickness and of a character that will endure high temperature and is a fair conductor of heat—such as asbestos paper—upon which is tightly wound in a spiral coil the resistance or electrical conductor C, consisting preferably of a fine metallic wire of highly-refractory character, beginning at one end of the cone and terminating at the other, the terminal D near the apex of the cone preferably being insulated, and brought back through a hole or passage in the core, and then united with one of the line-wires E, lying in the central passage, through the handle of the iron, the other line-wire F also leading through the

handle and being connected with the opposite terminal of the resistance at or near the base of the cone.

The outer shell or body G, consisting preferably of copper and having a conical exterior surface similar in shape to that of an ordinary soldering-iron, is employed for receiving the core and the electrical resistance wound thereon, to which end it is provided with a 10 tapering cavity corresponding to the taper of the core A, which cavity is first lined with a layer of an electrical insulating material H, similar to that already described for the core, after which the core, with its covering of insulation and resistance-wire, is inserted in position in the cavity and forced firmly against the walls thereof by means of a screw I, passing axially through the core and entering a screw-threaded socket in the tip of the shell 15 or body of the iron, thereby firmly binding the elements together under any desired pressure and securing them in position against displacement due to jarring or blows upon the iron in its practical use, or to the possible 20 shrinkage of the electrical insulations between the resistance and the body and core of the iron as a result of the great heat to which they are subjected.

This iron as a whole is secured to a handle 30 J, of any suitable form or material for convenience of manipulation, by means of a tube K, having a screw-thread connection at one end with the ferrule L of the handle and at its opposite end with a cap M, secured to the 35 core of the iron by means of the screws N, between which cap and the iron proper is inserted a layer of asbestos or some other heat-insulating material O, for preventing to the greatest possible degree the conduction of the 40 heat from the iron to the handle, the cap being preferably recessed on the inner face thereof, so as to provide an air-space for promoting the heat-insulation and at the same time furnish a passage for the disposal of the 45 resistance-wires.

From the foregoing description it will be readily seen that the heat evolved from the resistance or electrical conductor is utilized to the maximum degree, for with no cylindrical body portion to which the heat is first imparted, as has heretofore been the case, only the part of the iron which it is practically desired to heat—that is, the head or point thereof—will now be heated, and by the employment 50 of the core the point or head of the iron is rendered practically solid and will retain in the maximum degree the heat imparted thereto, and which has heretofore been dissipated through the heat-insulations and casing 55 of the iron body.

If desired, to insure the retention of the resistance in fixed relation to the core the whole may be provided in the conical surface thereof with a spiral groove, as illustrated in Figs. 3 and 4, into which the wire 60 and electrical insulation will be sunk, and

the convolutions of the wire thus retained in position against slipping upon the cone, this groove, while not absolutely essential to the successful operation of my invention, at the 70 same time being an advantageous feature of construction.

Other minor changes in details of construction may obviously be employed without departing from the spirit of my invention, so 75 long as the resistance or electrical conductor is confined within, so as to directly heat the point or head of the iron as distinguished from the indirect heating thereof, heretofore accomplished through the medium of the cylindrical body portion of the iron to the rear of the head.

Having described my invention, what I claim, and desire to secure by Letters Patent, 80 is—

1. In an electric soldering-iron, the combination, with the hollow body and the tapering core fitting within said body, of the resistance disposed about the core, and electrical insulations interposed between said resistance and the core and body, substantially 90 as described.

2. In an electric soldering-iron, the combination, with the hollow body and the tapering core fitting within said body, of the resistance disposed about said core, electrical insulations interposed between said resistance and the core and body, and means for binding said elements together under pressure, substantially as described.

3. In an electric soldering-iron, the combination, with the hollow body, the tapering core fitting within said body, the resistance disposed about said core, electrical insulations interposed between said resistance and the core and body, and means for binding said parts together, of the handle attached to said core and the heat-insulation interposed between said handle and the core and body, substantially as described.

4. In an electric soldering-iron, the combination, with the hollow conical body and the tapering core fitting within said body, of the resistance disposed about said core, electrical insulations interposed between said resistance and the core and body, and a screw passing axially through the core and engaging the body, so as to bind the said members firmly together under pressure, substantially as described.

5. In an electric soldering-iron, the combination, with the hollow body, of a tapering core having a spiral groove in the conical surface thereof and fitting within said body, of the resistance and electric insulations interposed 125 between said resistance and the core and body, substantially as described.

CHARLES E. CARPENTER.
